(57) **CLAIM**

The ornamental design for a writing device, as shown and described.

DESCRIPTION

1. Writing device
2. Writing device
- 1.1 : Front perspective
- 1.2 : Back perspective
- 1.3 : Front
- 1.4 : Right
- 1.5 : Back
- 1.6 : Left
- 1.7 : Top
- 1.8 : Bottom
- 2.1 : Front perspective
- 2.2 : Back perspective
- 2.3 : Front
- 2.4 : Right
- 2.5 : Left
- 2.6 : Back
- 2.7 : Top
- 2.8 : Bottom

A new, original, and ornamental design for a writing device, of which the following is a specification, reference being made to the accompanying drawings, forming a part hereof; figure 1.1 is a front perspective view of a writing device showing a first embodiment of my new design; figure 1.2 is a back perspective view thereof; figure 1.3 is a front view thereof; figure 1.4 is a right side view thereof; figure 1.5 is back view thereof; figure 1.6 is a left side view thereof; figure 1.7 is a top view thereof; figure 1.8 is a bottom view thereof; figure 2.1 is a front perspective view of a writing device showing a second embodiment of my new design; figure 2.2 is a back perspective view thereof; figure 2.3 is a front view thereof; figure 2.4 is a right side view thereof; figure 2.5 is left side view thereof; figure 2.6 is a back view thereof; figure 2.7 is a top view thereof; figure 2.8 is a bottom view thereof; features that are shown in equal sized broken lines form no part of the claimed designs.

1 Claim, 16 Drawing Sheets
